UNITED STATES PATENT OFFICE

2,614,677

GUIDE FOR OSCILLATORY LOADING HEAD

Charles N. Bebinger, New Philadelphia, Ohio, assignor to Joy Manufacturing Company, a corporation of Pennsylvania

Original application November 28, 1947, Serial No. 788,703. Divided and this application April 14, 1951, Serial No. 221,076

9 Claims. (Cl. 198—14)

1

This invention relates to loading apparatus and more particularly to a floor engaging guide for the oscillatory loading head of a mobile loading machine.

In a loading machine of the type disclosed in my Patent No. 2,234,071, granted March 4, 1941, some difficulty was encountered in properly positioning the vertically swingable, oscillatory loading head or vibratory gatherer of the machine, and at times the head or gatherer would be carried too high with respect to the bottom during the loading operation and at other times the head would be too low, resulting in undesired digging of its forward penetrating portion into the bottom. The present invention contemplates improvements over my earlier machine in that an improved floor engaging guide is provided for the vertically tilttable, oscillatory loading head or vibratory gatherer so that the forward penetrating edge of the head may be always properly positioned with respect to the bottom when the head is in its lowered operating position.

It is accordingly a primary object of the present invention to provide an improved mobile loading apparatus having improved guiding means for the oscillatory loading head thereof. Another object is to provide an improved supporting and guiding means for the forward gathering portion of a vibratory gathering head whereby undesired digging of the gathering portion into the bottom is substantially prevented. These and other objects and advantages of the invention will, however, hereinafter more fully appear.

This application is a division of my copending application Serial No. 788,703, filed November 28, 1947.

In the accompanying drawings there is shown for purposes of illustration one form which the invention may assume in practice.

In these drawings:

Fig. 1 is a plan view of the forward portion of a loading machine in which a preferred illustrative form of the invention is incorporated.

Fig. 2 is a side view of the forward portion of the loading machine shown in Fig. 1, with the loading head in its lowered, guided, operating position.

Fig. 3 is a longitudinal vertical section, on a somewhat reduced scale, taken substantially in the planes of line 3—3 of Fig. 1.

The loading machine in which the invention is embodied is of the crawler mounted, mobile, frontal attack type, although, evidently, the invention may be embodied in various other types of loading machines.

2

The loading machine generally comprises a mobile base 1 having a frame 2 mounted on conventional crawler treads 3 which may be driven and controlled to effect propulsion and steering of the machine in a well-known manner. Carried above the base frame is a vibratory or oscillatory gathering and elevating head 4 having, as shown in Fig. 1, a relatively wide front gathering head portion 5 and a relatively narrow troughlike portion 6 extending rearwardly of the widened portion, and arranged to gather and elevate the material to be loaded and to discharge the material rearwardly of the machine. The front widened gathering head portion 5 has a serrated front penetrating edge 7, and is formed with forwardly diverging sidewalls 8 which converge into the parallel longitudinal sidewalls 9 of the narrow troughlike portion 6, in the manner fully described in my Patent No. 2,234,071 above referred to.

The gathering and elevating head 4 is mounted for short-stroke oscillatory or rapid vibratory movement on the vertical sides of a tilttable upper frame 10, and is supported by pairs of parallel arms or links 11 which are pivotally mounted at 12 on the frame 10 and pivotally connected at 13 to the head 4. The tilttable frame 10 is pivotally mounted at 14 on the rearward portion of the base frame 2 to swing in a vertical plane with respect to the base and a pair of upright extensible hydraulic jacks 15 are arranged at the opposite sides of the forward portion of the base frame and are pivotally connected at their lower ends at 16 to the base frame and pivotally connected at their upper ends at 17 to the upper portion of the tilttable frame 10. By supplying liquid under pressure to the cylinders of these jacks the tilttable frame together with the loading head may be swung upwardly about the pivot 14 with respect to the base, and when liquid is vented from the cylinders of these jacks the frame and loading head may be swung downwardly. By trapping liquid within the jack cylinders the tilttable frame and the loading head may be locked in adjusted position. The upper tilttable frame 10 has suitable curved guides 18 slidably engaging arcuate guideways 19 on the forward portion of the base frame for guiding the tilttable frame 10 as it is swung in a vertical direction about its pivot 14.

Carried by the tilttable frame 10 is a motor 21 (see Fig. 3) which drives a transverse shaft 22 to which eccentrics 23 are secured, and these eccentrics effect actuation of longitudinal connecting rods 24. The front ends of these con-

necting rods are pivotally connected to the lower ends of crank arms 25 pivoted at 26 on the frame 10 and which are secured to crank arms 27, the latter in turn being pivotally connected at 28 to links 29. The links 29 are pivotally connected at 30 to arms 31 integral with the front hanger links 11. Thus, when the eccentrics 23 are driven by the motor 21, the gathering and elevating head 4 is rapidly oscillated back and forth or vibrated on its arm and link mountings, in the manner fully described in my copending application Serial No. 788,703 mentioned above, to effect gathering and loading of the loose material on the floor.

In this improved construction, to prevent the front penetrating edge 7 of the widened front portion 5 of the head from digging into the bottom during the loading operation, the forward part of the frame 10 has forward side projections 32 extending forwardly and outwardly beneath the head and provided with bottom floor engaging shoes 33, and with upper guide portions 34 engaging the straight outer sides 35 of the forward widened portion of the head for guiding the latter during its oscillation or vibratory motion. These floor engaging shoes 33 serve to prevent the penetrating edge of the head from running into the floor in the lowered position of the head, as shown in Fig. 2 and at all times adequately support the head in its proper position with respect to the floor during the gathering and loading operation.

The loading machine may be propelled about the mine and maneuvered with respect to the work by the crawler treads 3 in a well-known manner. During transport, the forward ends of the gathering and elevating head 4 and the tiltable upper frame 10 are held raised above the floor level by the hydraulic jacks 15, and when the working place is reached, the jacks may be operated to lower the frame shoes 33 into contact with the floor to bring the penetrating edge 7 of the head into close adjacency with the floor. The motor 21 may then be operated to impart, through the arms and links, a rapid oscillatory or vibratory motion to the head in a direction generally lengthwise thereof, and, concurrently, the crawler treads may be operated to advance the head into the material to be loaded, to feed the widened front head portion 5 beneath the loose material. As the head is rapidly oscillated or vibrated, the loose material is gathered thereon and moved rearwardly and upwardly along the trough portion 6 to discharge at the elevated rear end of the latter, all in the manner fully disclosed in my above mentioned copending application. Thus, the gathering and elevating head rapidly and continuously gathers and conveys the material, and the material moves in a substantially steady stream rearwardly and upwardly along the trough to discharge. The forward guiding portions on the tiltable upper frame with its shoes 33 slidingly engaging the floor provide adequate guides for the vibrating head and serve to prevent digging of the forward penetrating edge of the head into the floor or bottom.

As a result of this invention, an improved loading apparatus is provided wherein the vibratory loading head of the machine is adequately supported and guided during the gathering and loading operation. By the provision of the shoes and guides on the frame projections beneath the vibratory head the penetrating edge of the latter is prevented from inadvertently digging into the floor when in lowered position, and serve ade-

quately to guide the forward portion of the head during its operation. Other manners of use and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a material loading apparatus, the combination comprising a support, a frame pivotally mounted on said support to swing in vertical planes relative thereto about a horizontal axis, said frame having a forward floor engaging portion rigidly connected thereto for limiting downward swinging movement of said frame, and a vibratory gathering and elevating head mounted in a forwardly and downwardly inclined position on said frame for vibratory gathering and elevating movement relative thereto and having a front gathering portion provided with a penetrating edge, said rigidly connected floor engaging portion of said frame underlying and engaging said front gathering portion and providing a guideway for the latter to maintain the penetrating edge thereof in the desired relation to the floor.

2. In a material loading apparatus, the combination comprising a support, a frame pivotally mounted on said support to swing in vertical planes relative thereto about a horizontal axis, said frame having laterally spaced side portions each provided with a floor engaging shoe for limiting downward swinging movement of said frame, and a vibratory gathering and elevating head mounted in a forwardly and downwardly inclined position on said frame for vibratory gathering and elevating movement relative thereto and having a front gathering portion provided with a penetrating edge, said spaced side portions of said frame extending along the sides of said front gathering portion beneath the latter and having upper guides engaging said gathering portion to maintain the penetrating edge thereof in the desired relation to the floor.

3. In a material loading apparatus, the combination comprising a support, means for mounting said support for adjustment in a vertical direction, an oscillatory gatherer having a transverse forward penetrating edge, and means for mounting said gatherer on said support for oscillatory movement relative thereto and having a forward receiving end, and said support having a floor engaging portion rigidly connected thereto and underlying the receiving end of said gatherer and providing a guideway for the latter for maintaining said penetrating edge of said gatherer in the desired relation to the floor, said guideway provided by said rigid floor-engaging portion extending generally in the direction of oscillation of said gatherer.

4. In a material loading apparatus, the combination comprising a supporting frame, an oscillatory gatherer having a front penetrating edge, means for mounting said gatherer on said frame for longitudinal oscillatory movement with respect thereto with said penetrating edge disposed near the floor level and guiding projections rigidly secured to said frame and extending forwardly beneath said gatherer, said projections

having shoes engaging the floor near said penetrating edge and guides extending generally in the direction of oscillation of said gatherer and engaging the sides of the forward portion of said gatherer, for guiding said gatherer during its oscillation and for preventing digging of said penetrating edge into the floor.

5. In a material loading apparatus, the combination comprising a mobile base movable over a floor surface, a frame carried by said base and extending lengthwise of said base with its forward portion in advance of said base, an oscillatory gatherer and loading head mounted on said frame for longitudinal oscillatory movement with respect thereto, said head projecting forwardly in advance of said frame and having a front penetrating edge disposable near the floor surface, and guiding means carried by and rigidly connected to the forward portion of said frame and having shoes engaging the floor in adjacency to said forward penetrating edge and lateral guide portions engaging the sides of the forward portion of said head, said guide portions providing a guideway extending generally in the direction of oscillation of said head, whereby said head is guided during oscillation thereof and digging of said penetrating edge into the floor is prevented.

6. In a material loading apparatus, the combination comprising a support, a frame pivotally mounted on said support to swing in vertical planes relative thereto about a horizontal axis, said frame having a forwardly projecting portion rigidly connected thereto and provided with a floor-engaging shoe for limiting downward swinging movement of said frame, and a vibratory gathering and elevating head mounted in a forwardly and downwardly inclined position on said frame for vibratory gathering and elevating movement relative thereto and having a front gathering portion provided with a transverse penetrating edge, said forwardly projecting frame portion having laterally spaced side portions extending along the sides of said front gathering

portion beneath the latter and having upper guides engaging the sides of said gathering portion and cooperating to provide a guideway extending generally in the direction of oscillation of said head for guiding the latter and to maintain said penetrating edge in the desired relation to the floor.

7. A material loading apparatus as set forth in claim 6 wherein said forwardly projecting frame portion has lateral side portions each providing a floor-engaging shoe, said laterally spaced side portions supporting said upper guides and extending along the side edges of said front gathering portion.

8. A material loading apparatus as set forth in claim 7 wherein the sides of said front gathering portion diverge forwardly and outwardly and said upper guides of said laterally spaced side portions engage said diverging sides of said front gathering portion.

9. A material loading apparatus as set forth in claim 8 wherein said diverging sides of said front gathering portion have angularly disposed plane guiding surfaces and said spaced side portions have upstanding forward guides with which said plane surfaces slidably engage during oscillation of said head.
